Patented Aug. 29, 1922.

Inventor
Ernest L. Rosenburgh
By his Attorney
E. M. Bentley

UNITED STATES PATENT OFFICE.

ERNEST L. ROSENBURGH, OF ROME, NEW YORK, ASSIGNOR TO ROME METALLIC BED-STEAD COMPANY, OF ROME, NEW YORK, A CORPORATION OF NEW YORK.

DESIGN FOR A BEDSTEAD END FRAME.

61,424.

Specification for Design.

Patented Aug. 29, 1922.

Application filed January 7, 1922. Serial No. 91. Term of patent 7 years.

To all whom it may concern:

Be it known that I ERNEST L. ROSENBURGH, a citizen of the United States, residing at Rome, county of Oneida, State of New York, have invented a new, original, and ornamental Design for Bedstead End Frames, of which the following is a specification.

In the accompanying drawing, the figure

is a perspective view illustrating a bedstead end-frame embodying my invention.

I claim:

The ornamental design for a bedstead-end frame as shown.

In testimony whereof, I have hereunto set my hand at Rome, Oneida County, State of New York, this 4th day of January, 1922.

ERNEST L. ROSENBURGH.
